KNOCKDOWN KNEELING BENCH

George B. Laufer, St. Louis, Mo.

Application September 9, 1933, Serial No. 688,807

3 Claims. (Cl. 155—166)

This invention relates to a kneeling bench such as is used in funeral equipment by funeral directors for the benefit of mourners in offering prayer, the invention pertaining more particularly to the knock-down form of kneeling bench for convenience of conveying and packing for transportation thereof from place to place.

An object of the invention is to provide a kneeling bench, of a simplified knock-down form.

10 Another object of the invention is in providing a knock-down kneeling bench of a minimum of demountable parts.

15 A further object of the invention is to provide the parts of the kneeling bench which sustain the resting weight of the occupant with keying devices which are interlocked with the supporting ends of the bench, and are thereby securely held by the weight of the occupant.

20 Other and further objects will appear in the specification and be specifically pointed out in the appended claims, reference being had to the accompanying drawing, exemplifying the invention, and in which:—

25 Figure 1 is a front elevation of this improved knock-down kneeling bench.

Figure 2 is a vertical transverse section taken approximately on the line II—II of Fig. 1.

Figure 3 is a side elevation of one of the end members of the kneeling bench.

30 Figure 4 is a fragmentary section taken approximately on the line IV—IV of Fig. 2.

Figure 5 is an inverted fragmentary perspective view of an end of the kneeling member of the bench.

35 Referring to the accompanying drawing, this improved knock-down kneeling bench comprises a minimum of demountable parts which includes, a pair of end members 1, a kneeling member 2, an arm rest 3 and a drape rail 4, the parts 2 and 3 at their ends having interlocking engagement with the end members 1 for sustaining the parts in assembled positions for use.

40 The parts provided on each of the end members 1 for interlocking with the ends of the kneeling member 2, are a pair of vertically disposed spaced brackets 5 secured by screws 6 to the base 7 of respective end members, each bracket having a vertically disposed socket 8. For insertion into the sockets 8 of respective pairs of brackets 5, are pins 9 which are disposed in pairs on respective ends of the kneeling member 2, each pair of pins 9 being depended from respective brackets 10 which are secured to the under side of the kneeling member 2 by screws 11.

55 The arm rest 3 is provided on the under side of

each end with a bracket 12 from which a pin 13 is depended, each of said pins being for engaging cooperation with a socket 14 of respective brackets 15, one of which is secured to each end member 1 adjacent the upper end thereof by screws 16. The bracket 15 on each end member 1 is inclined from the vertical so that the upper surface of the arm rest 3 will be disposed inclined towards the occupant when kneeling on the kneeling member 2 so that the arms of the occupant can be comfortably disposed.

5 Extending forwardly from each bracket 15 is a hook member 17 for the reception of the ends of the drape rail 4 after the drape 18 has been hung from the rail.

10 In assembling this knock-down kneeling bench, the pins 9 on one end of a kneeling member 2 are engaged in respective sockets 8 of a pair of brackets 5 on one of the end members, after which the pins 9 on the opposite end of the kneeling member 2 are engaged in respective sockets 8 of the brackets 5 on the other end member 1.

15 The drape rail 4 having the drape 18 hung thereon is then engaged on the hook members 17, after which the arm rest 3 is manipulated to engage the end disposed pins 13 in respective sockets 14 of the brackets 15 and when the arm rest 3 is secured in proper position as shown in Fig. 3, the forward edge of the under side of the arm rest will be disposed above the drape rail 4, and in this position will cooperate therewith to prevent the drape rail being lifted from the hook members 17.

20 Kneeling of the occupant on the member 2 will obviously firmly seat the pins 9 in the sockets of the brackets 5 and the weight of the resting arms of the occupant on the arm rest 3 will firmly seat the pins 13 of the arm rest in respective brackets 15.

25 In dismantling the kneeling bench, the arm rest 3 is raised so that the pins 13 thereof will be disengaged from the sockets of respective brackets 15 and the drape rail 4 is then removed from the hook members 17. The kneeling member 2 is then elevated so that the pins 9 thereof will be disengaged from the sockets of respective brackets 5, thus freeing the members 1. The parts are then ready for packing together for transportation or storing.

30 Obviously constructional modifications of the device are possible without departing from the spirit of the present invention and therefore it is to be understood that it is not necessary to limit the invention by the terms used in the foregoing

description, excepting such as the state of the art may require.

What I claim is:—

1. A kneeling bench comprising end members, a kneeling member secured to the end members, an arm rest demountably secured at its ends to the respective end members, a drape rail, and means demountably securing the drape rail beneath and adjacent the arm rest member, the 10 proximity of the arm rest member to the drape rail preventing removal of the drape rail from the securing means.

2. A kneeling bench comprising end members, a kneeling member secured to the end members, an arm rest member demountably secured at its 15 ends to the respective end members, a drape rail, and means demountably securing the drape

rail beneath the arm rest member with which the arm rest member is cooperable, for preventing lifting removal of the drape rail.

3. A kneeling bench comprising end members, a kneeling member and an arm rest member, socket brackets carried by said end members, said kneeling member and said arm rest member each having depending securing pins engageable in respective socket brackets of said end members for securing all of said members in assembled 10 positions, a drape rail, and means removably mounting the drape rail beneath the arm rest member with which the arm rest member is cooperable, for preventing removal of the drape rail when the members are assembled. 15

GEORGE B. LAUFER.
